UNITED STATES PATENT OFFICE.

ISAAC ST. CLAIR GOLDMAN, DECEASED, LATE OF LOS ANGELES, CALIFORNIA, BY ELLA E. GOLDMAN, EXECUTRIX, OF LOS ANGELES, CALIFORNIA, ASSIGNOR OF ONE-HALF TO L. S. HACKNEY, OF ST. PAUL, MINNESOTA.

LOCK.

1,078,192.

Specification of Letters Patent.

Patented Nov. 11, 1913.

Application filed June 6, 1912. Serial No. 702,017.

To all whom it may concern:

Be it known that ISAAC ST. CLAIR GOLDMAN, deceased, formerly a citizen of the United States and a resident of Los Angeles, in the county of Los Angeles, State of California, did invent certain new and useful Improvements in Locks, of which the following is a specification.

The invention relates to mortise locks and 10 was designed as an improvement over the lock shown and described in Letters Patent of the United States No. 927,139, issued July 6, 1909.

A further object is to simplify the construction of the lock, dispensing with unnecessary parts and thereby effecting a considerable economy in the manufacture of the article.

The invention consists generally in various constructions and combinations, all as hereinafter described and particularly pointed out in the claims.

In the accompanying drawings forming part of this specification, Figure 1 is a sectional view showing a lock embodying the invention, with the latch projected, Fig. 2 is a similar view, showing the latch withdrawn, Fig. 3 is a vertical sectional view showing the position of the key in the lock 20 preparatory to operating the tumblers, Fig. 4 is an edge view of the lock, Fig. 5 is a sectional view with the locking latch removed, illustrating the means for setting the tumblers to allow the latch to be withdrawn

35 without the use of the key, Fig. 6 is a sectional view on the line $\alpha-\alpha$ of Fig. 5, Fig. 7 is a horizontal sectional view through the upper portion of the lock, Fig. 8 is a similar view through the lower portion of the lock.

40 In the drawing, 2 represents the lock casting, adapted to be fitted into a mortise in the door and secured therein in the usual way.

45 3 is a latch having the usual beveled face 4 at its outer end and provided at its inner ends with a T-shaped head 5. This latch is adapted to slide horizontally through an opening 6 in the casing and is normally held in its projected position by means of a spring 7 which bears on the latch at one end

and at its other end rests on the bottom of 50 the casing and preferably has an intermediate loop or eye that is passed around a pin 8 that is mounted in the casing of the lock.

9 is a rotating barrel journaled at its ends in the casing and having the usual socket 10 55 therein for the knob spindle. A lug 11 is mounted on this barrel and a plate 12 has a shoulder 13 in the path of this lug, said plate being slidably supported between the upper wall of the casing and a pin 14 that 60 is mounted in the wall of the casing. An arm 15 depends from said plate and has a horizontal recess 16 therein.

A series of tumblers 17 are pivoted at 18 and normally held by springs 19 in contact 65 with a wall 20, said tumblers varying in width so that when they are resting upon said wall they will be out of alinement with one another and all of them will be out of register with the recess 16. Upward movement of these tumblers is limited by a stud 21 having a socket therein for a screw 22 which passes through a face plate 23 which, upon being removed, allows access to the mechanism of the lock. The plate 12 also 70 has an arm 24 thereon provided with an offset 25 that is adapted to engage the T-head 5 of the latch and retract the latch against the tension of the spring 7 when the tumblers are set in position to allow movement 80 of the plate 12.

A bell crank 26 is pivoted on the pin 8 and has an arm 27 projecting upwardly therefrom into contact with a wing 28 which projects from the barrel 9, the upper end of 85 said arm being preferably curved inwardly toward said barrel and normally resting on the upper edge of said wing. Said bell crank also has an arm 39 extending horizontally and provided with a head 30 in which 90 a socket 31 is formed to receive the key 32, said socket being open at each end and allowing the insertion of the key from either side of the lock. The wing 28, in addition to its function of oscillating the bell crank, 95 is adapted to contact with the shoulder 25 on the arm 24 and actuate the plate 12 to withdraw the locking latch when the tumblers

are set in their releasing position, as indicated in Fig. 5, and the knob barrel is rotated toward the left. The key is provided with a series of upwardly projecting key-wards 33 that are adapted to enter a corresponding number of holes 34 in the plate 20 and contact with the lower edges of the tumblers resting on said plate. The key-wards vary in length and when they are thrust up 10 through the holes in the plate 20 the movement of the tumblers will be timed so that their edges will register with one another and with the recess in the plate 12 and allow the plate to be retracted to engage the latch 15 and withdraw it also. This will take place after the key is inserted into the socket and when the knob is turned.

Referring to Fig. 1, the arm 27 is shown in contact with the upper edge of the wing 20 and when the knob and the barrel 9 are rotated toward the right the arm will move out on the curved outer edge of the wing and raise the arm 27 and push the key-wards through the holes 34 and lift the tumblers 25 simultaneously until they register with the recess 16. This movement of the arm 27 will be against the tension of a spring 35 which normally tends to hold the bell crank in the position shown in Fig. 1. At the same 30 time that the knob is turned, the arm 11 will engage the shoulder 13, move the plate 12 and retract the latch 31 to the position indicated in Fig. 2, thereupon unlocking the door.

It is sometimes desirable to set the lock so 35 that the door may be opened without the use of a key. A crank 36 is therefore mounted in the bottom of the casing having a finger piece 37 accessible through the wall 40 of the casing and held against outward movement by a pin 38 engaging the bent end of the crank. An arm 39 is pivoted on the pin 8 and has a plate 40 at one end to contact with said crank and an upper edge in 45 position to engage the lower edges of the tumblers 17 and lift them into alignment with one another and in position to register with the recess 16. When this has been done the knob may be turned and the latch or bolt 50 retracted without the use of a key.

From the foregoing description it will be noted that to unlock the door it is only necessary to insert the key into the socket and turn the knob, no manual movement of the key being necessary, the turning of the knob raising the key until its wards engage the tumblers and lift them all simultaneously to allow retraction of the plate 12 and the locking latch.

In various ways the details of construction 60 may be modified and still be within the scope of this invention.

What is claimed is—

1. The combination, with a casing and a

sliding latch or bolt, of a plate having means 65 for engaging and retracting said latch, a series of tumblers arranged to normally prevent movement of said plate, a rotating knob barrel, means actuated by the rotation of said barrel for moving a key into engagement with said tumblers to actuate them and release said plate and simultaneously move said plate and retract said latch.

2. The combination, with a casing and a locking latch or bolt therefor, of a sliding 75 plate having means to engage and retract said latch and provided with a recess therein, a series of tumblers normally out of alignment with said recess, a rotating knob barrel, a bell crank having a key socket to 80 receive a key, said barrel having means to engage said bell crank and oscillate it during the initial movement of said barrel to move the key into engagement with said tumblers and align them with said recess, 85 said barrel also having means to engage said plate subsequent to the movement of said bell crank and actuate it to retract said latch.

3. The combination, with a casing and a 90 locking latch or bolt therefor, of a sliding, recessed plate having means to engage and retract said latch, a series of tumblers normally out of alignment with said recess and locking said plate against retraction, a rotating knob barrel having a wing thereon, an oscillating bell crank having one arm arranged to contact with said wing, the other arm of said bell crank having a key socket 95 therein adapted to receive a key, the initial rotation of said knob barrel oscillating said bell crank and moving the key into engagement with said tumblers to align them with one another and with said recess, and means for actuating said plate to retract said latch. 100

4. The combination, with a casing and a locking latch therefor, of a series of tumblers pivoted therein, a plate arranged to support said tumblers and having a series of holes therein, means having a key socket 110 therein, means normally locked by said tumblers for retracting said latch, a knob barrel and mechanism actuated by the rotation of said barrel for thrusting the key wards through said holes to actuate said tumblers 115 and release said latch retracting means.

5. The combination, with a lock casing and a locking latch or bolt therefor, of a series of pivoted tumblers, means having a key socket therein, means normally locked 120 by said tumblers for retracting said latch, a knob barrel, and mechanism actuated by the rotation of said barrel for moving the key into engagement with said tumblers and releasing said latch retracting means. 125

6. The combination, with a lock casing and a locking latch, of a series of pivoted tumblers, a knob, and mechanism actuated

by the rotation of said knob in either direction for moving a key to actuate said tumblers and release said latch.

7. The combination with a lock casing and a locking latch therefor, of pivoted tumblers, a knob barrel, and mechanism actuated by the rotation of said barrel in either direction for moving a key into engagement with said tumblers and releasing said latch.

In witness whereof, I have hereunto set my hand this 20th day of April, 1912.

ELLA E. GOLDMAN,
*Executrix of the last will and testament of
Isaac St. Clair Goldman, deceased.*
